BELT BUCKLE

Filed Feb. 24, 1923

FIG. 5.

FIG. 6.

Inventor
MARY STARMER

Attorney
Freelon B. Brock

UNITED STATES PATENT OFFICE.

MARY STARMER, OF NEWPORT NEWS, VIRGINIA.

BELT BUCKLE.

Application filed February 24, 1923. Serial No. 620,960.

To all whom it may concern:

Be it known that I, MARY STARMER, a citizen of the United States, residing at Newport News, in the county of Warwick and 5 State of Virginia, have invented certain new and useful Improvements in Belt Buckles, of which the following is a specification.

The device of the present invention is designed to provide a quick detachable connection for use with belts or garment supporters of the waistline type, which may be adjusted with facility, and is adapted for use by both men and women.

By the utilization of the invention the 15 main buckle and the adjusting buckle, the latter for use in varying the length of the belt, may be quickly and securely affixed at the respective ends of the belt, and the connecting members of the main buckle may be 20 joined with convenience. When so joined the connecting members are well braced and retained in position to present a neat and well groomed appearance for the wearer of the belt.

25 The invention consists in certain novel combinations and arrangements of parts, as will be hereinafter pointed out and claimed, whereby the above conditions and desirable results are accomplished.

30 In the accompanying drawings I have illustrated one example of the physical embodiment of my invention wherein the parts are combined and arranged in accordance with the principles of my invention.

35 Figure 1 is a front view showing the two joined ends of a belt equipped with the device of my invention.

Figure 2 is a view as seen from the rear in Figure 1.

40 Figure 3 is a longitudinal sectional view showing the general relation of parts.

Figure 4 is a view at the inner side of the belt buckle.

Figure 5 is a view of the buckle fastening-loop.

Figure 6 is a view at the inner side of the adjusting buckle.

The ends of the belt are indicated by the letters A and B and have respective loops 50 A' and B', the ends of which are designated A², B² as in Figure 3. The belt may be of suitable material and made in accordance with various styles or designs.

55 The buckle plate 1 is preferably of metal and stamped or otherwise fashioned to shape, and may be ornamented or embel-

lished on its front in customary manner. At the rear the plate 1 is fashioned with a vertical, end bar 2, extending across the plate near one end, by means of which a 60 guide slot 3 is provided for the end A of the belt. At its upper and lower edges the buckle plate is provided with angular flanges or braces 4, 4, extending approximately throughout its length, and forming 65 top and bottom walls for an enclosure at the rear of the plate. Within the enclosure and at the back of the plate a buckle hook 5 is located, said hook being formed as an integral part of a rectangular frame 6 of wire, 70 which, by means of its top and bottom bars is rigidly held within the enclosure of the buckle plate by inturned retaining flanges 7, 7. The frame is fashioned by suitable tools and the hook 5 extends within the 75 frame, and is also slightly offset from the inner face of the buckle plate. At the junctions of the hook with the frame, an upper notch 5' is provided and a lower shoulder 6' is fashioned, as best seen in Figure 4.

The ends of the wire forming the frame are secured together and one of these ends is fashioned as a prong or pin 8, which is designed to secure the end A² of the loop A' 80 after the loop has been made around the side bar of the frame 6, as shown in Figure 3.

The fastening link for connection with the buckle hook 5 is preferably made up of 90 a single piece of wire and fashioned with a pair of loops 9 and 10, arranged parallel, and of the required length for their respective uses. The loop 9 it will be apparent is designed to be hung or suspended on the 95 hook 5, the upper and lower portions of the loop, respectively, engaging the notch 5' and shoulder 6' of the hook frame, as seen in Figure 2 where the loop is shown secured against displacement. The longer 100 loop 10 has the loop B' of the belt-end B passed therethrough, and the fastening link is fashioned with a pair of arms 11 located within the loop as a brace for the loop B' and to maintain the fastening link in position. These arms also afford a finger hold 105 for the wearer of the belt when the fastening link is being slipped over the hook 5.

The adjusting plate 12 on the end B of the belt has at its rear a gripping jaw 13, 110 which may be toothed, or plane at its edge for co-action with the belt in connection

with the belt loop B' and its end B², and the plate forming part of the adjusting buckle is slidable on the web of the belt at B. At the rear of the adjusting buckle an approximately rectangular loop or frame 14 is hinged by turning in the stamped out ears 15 of the jaw 13, and these ears retain the loop 14 for attachment of the loop B'. The ends 16 and 17 of the loop are fashioned as prongs extending at right angles 10 from the frame toward the inner face of the plate 12, and these prongs pass through the end B² of the loop B' to anchor the end of the belt within the adjusting plate. It will be apparent that the end B² is 15 first passed between the jaw 13 and the prongs 16 and 17, thence through the loop 10 and brought back again and the end secured within the buckle against the inner 20 face of the belt by the prongs 16, 17 as seen in Figure 3, after which a pull on the belt will cause the prongs to engage in the end B², and the jaw 13, whether serrated as shown, or provided with a plain edge, will 25 engage the belt as in Figure 3, to hold the parts in proper position.

Various changes may be made in the device within the scope of my claims without departing from the spirit of my invention. As for instance the plate 13 30 may have a plain or smooth edge instead of the serrated edge, and one spur may be substituted for the two spurs 16 and 17 if desired.

Having thus fully described my invention, what I claim as new and desire to secure by Letters Patent is:—

1. The combination in a belt-buckle having a hook-frame secured at the rear thereof, and a hook fashioned within said frame, of a rigid prong on said frame adapted to engage and secure a belt loop, and a detachable fastening loop for coaction with said hook. 35

2. The combination in a belt-buckle having upper and lower retaining flanges, of a hook-frame secured within said flanges and an integral hook within said frame, of a detachable fastening member having a loop for co-action with said hook at one 40 end of the belt, and means on the hook frame for securing a belt loop. 45

3. The combination with a belt-buckle having a hook frame and retaining flanges on said buckle for the frame, said frame fashioned with a hook and complementary notch and shoulder, of a fastening member including a loop adapted to engage over 50 said hook and co-act with said notch and shoulder. 55

4. The combination in an adjusting buckle having a rear gripping jaw for a belt, of a loop member secured within said jaw and adapted to retain the loop end of a belt, means on the loop-member to engage said 55 loop-end, and a detachable fastening member carried by the belt-loop. 60

(Mrs.) MARY STARMER.
